US00D867594S

(12) **United States Design Patent** (10) **Patent No.:** **US D867,594 S**
(45) **Date of Patent:** **** Nov. 19, 2019**

(54) **PROSTHETIC HEART VALVE**

(71) Applicant: **Edwards Lifesciences Corporation, Irvine, CA (US)**

(72) Inventors: **Da-Yu Chang, Irvine, CA (US); Brian S. Conklin, Orange, CA (US)**

(73) Assignee: **Edwards Lifesciences Corporation, Irvine, CA (US)**

(**) Term: **15 Years**

(21) Appl. No.: **29/579,402**

(22) Filed: **Sep. 29, 2016**

CLAIM

The ornamental design for a prosthetic heart valve, as shown and described.

DESCRIPTION

FIG. 1 is a perspective view of an embodiment of a prosthetic heart valve.
 FIG. 2 is a front view of the embodiment of the prosthetic heart valve shown in FIG. 1.
 FIG. 3 is a back view of the embodiment of the prosthetic heart valve shown in FIG. 1.
 FIG. 4 is a left view of the embodiment of the prosthetic heart valve shown in FIG. 1.
 FIG. 5 is a right view of the embodiment of the prosthetic heart valve shown in FIG. 1.
 FIG. 6 is a top view of the embodiment of the prosthetic heart valve shown in FIG. 1.
 FIG. 7 is a bottom view of the embodiment of the prosthetic heart valve shown in FIG. 1.
 FIG. 8 is a perspective view of another embodiment of a prosthetic heart valve.
 FIG. 9 is a front view of the embodiment of the prosthetic heart valve shown in FIG. 8.
 FIG. 10 is a back view of the embodiment of the prosthetic heart valve shown in FIG. 8.
 FIG. 11 is a left view of the embodiment of the prosthetic heart valve shown in FIG. 8.
 FIG. 12 is a right view of the embodiment of the prosthetic heart valve shown in FIG. 8.
 FIG. 13 is a top view of the embodiment of the prosthetic heart valve shown in FIG. 8.

FIG. 14 is a bottom view of the embodiment of the prosthetic heart valve shown in FIG. 8.

FIG. 15 is a perspective view of another embodiment of a prosthetic heart valve.

FIG. 16 is a front view of the embodiment of the prosthetic heart valve shown in FIG. 15.

FIG. 17 is a back view of the embodiment of the prosthetic heart valve shown in FIG. 15.

FIG. 18 is a left view of the embodiment of the prosthetic heart valve shown in FIG. 15.

FIG. 19 is a right view of the embodiment of the prosthetic heart valve shown in FIG. 15.

FIG. 20 is a top view of the embodiment of the prosthetic heart valve shown in FIG. 15.

FIG. 21 is a bottom view of the embodiment of the prosthetic heart valve shown in FIG. 15.

FIG. 22 is a perspective view of another embodiment of a prosthetic heart valve.

FIG. 23 is a front view of the embodiment of the prosthetic heart valve shown in FIG. 22.

FIG. 24 is a back view of the embodiment of the prosthetic heart valve shown in FIG. 22.

FIG. 25 is a left view of the embodiment of the prosthetic heart valve shown in FIG. 22.

FIG. 26 is a right view of the embodiment of the prosthetic heart valve shown in FIG. 22.

FIG. 27 is a top view of the embodiment of the prosthetic heart valve shown in FIG. 22.

FIG. 28 is a bottom view of the embodiment of the prosthetic heart valve shown in FIG. 22.

FIG. 29 is a perspective view of another embodiment of a prosthetic heart valve.

FIG. 30 is a front view of the embodiment of the prosthetic heart valve shown in FIG. 29.

FIG. 31 is a back view of the embodiment of the prosthetic heart valve shown in FIG. 29.

FIG. 32 is a left view of the embodiment of the prosthetic heart valve shown in FIG. 29.

FIG. 33 is a right view of the embodiment of the prosthetic heart valve shown in FIG. 29.

FIG. 34 is a top view of the embodiment of the prosthetic heart valve shown in FIG. 29.

FIG. 35 is a bottom view of the embodiment of the prosthetic heart valve shown in FIG. 29.

FIG. 36 is a perspective view of another embodiment of a prosthetic heart valve.

FIG. 37 is a front view of the embodiment of the prosthetic heart valve shown in FIG. 36.

FIG. 38 is a back view of the embodiment of the prosthetic heart valve shown in FIG. 36.

FIG. 39 is a left view of the embodiment of the prosthetic heart valve shown in FIG. 36.

FIG. 40 is a right view of the embodiment of the prosthetic heart valve shown in FIG. 36.

FIG. 41 is a top view of the embodiment of the prosthetic heart valve shown in FIG. 36.

FIG. 42 is a bottom view of the embodiment of the prosthetic heart valve shown in FIG. 36.

FIG. 43 is a perspective view of another embodiment of a prosthetic heart valve.

FIG. 44 is a front view of the embodiment of the prosthetic heart valve shown in FIG. 43.

FIG. 45 is a back view of the embodiment of the prosthetic heart valve shown in FIG. 43.

FIG. 46 is a left view of the embodiment of the prosthetic heart valve shown in FIG. 43.
FIG. 47 is a right view of the embodiment of the prosthetic heart valve shown in FIG. 43.
FIG. 48 is a top view of the embodiment of the prosthetic heart valve shown in FIG. 43.
FIG. 49 is a bottom view of the embodiment of the prosthetic heart valve shown in FIG. 43.
FIG. 50 is a perspective view of another embodiment of a prosthetic heart valve.
FIG. 51 is a front view of the embodiment of the prosthetic heart valve shown in FIG. 50.
FIG. 52 is a back view of the embodiment of the prosthetic heart valve shown in FIG. 50.
FIG. 53 is a left view of the embodiment of the prosthetic heart valve shown in FIG. 50.
FIG. 54 is a right view of the embodiment of the prosthetic heart valve shown in FIG. 50.
FIG. 55 is a top view of the embodiment of the prosthetic heart valve shown in FIG. 50.
FIG. 56 is a bottom view of the embodiment of the prosthetic heart valve shown in FIG. 50.
FIG. 57 is a perspective view of another embodiment of a prosthetic heart valve.
FIG. 58 is a front view of the embodiment of the prosthetic heart valve shown in FIG. 57.
FIG. 59 is a back view of the embodiment of the prosthetic heart valve shown in FIG. 57.
FIG. 60 is a left view of the embodiment of the prosthetic heart valve shown in FIG. 57.
FIG. 61 is a right view of the embodiment of the prosthetic heart valve shown in FIG. 57.
FIG. 62 is a top view of the embodiment of the prosthetic heart valve shown in FIG. 57.
FIG. 63 is a bottom view of the embodiment of the prosthetic heart valve shown in FIG. 57.
FIG. 64 is a perspective view of another embodiment of a prosthetic heart valve.
FIG. 65 is a front view of the embodiment of the prosthetic heart valve shown in FIG. 64.

FIG. 66 is a back view of the embodiment of the prosthetic heart valve shown in FIG. 64.
FIG. 67 is a left view of the embodiment of the prosthetic heart valve shown in FIG. 64.
FIG. 68 is a right view of the embodiment of the prosthetic heart valve shown in FIG. 64.
FIG. 69 is a top view of the embodiment of the prosthetic heart valve shown in FIG. 64.
FIG. 70 is a bottom view of the embodiment of the prosthetic heart valve shown in FIG. 64.
FIG. 71 is a perspective view of another embodiment of a prosthetic heart valve.
FIG. 72 is a front view of the embodiment of the prosthetic heart valve shown in FIG. 71.
FIG. 73 is a back view of the embodiment of the prosthetic heart valve shown in FIG. 71.
FIG. 74 is a left view of the embodiment of the prosthetic heart valve shown in FIG. 71.
FIG. 75 is a right view of the embodiment of the prosthetic heart valve shown in FIG. 71.
FIG. 76 is a top view of the embodiment of the prosthetic heart valve shown in FIG. 71.
FIG. 77 is a bottom view of the embodiment of the prosthetic heart valve shown in FIG. 71.
FIG. 78 is a perspective view of another embodiment of a prosthetic heart valve.
FIG. 79 is a front view of the embodiment of the prosthetic heart valve shown in FIG. 78.
FIG. 80 is a back view of the embodiment of the prosthetic heart valve shown in FIG. 78.
FIG. 81 is a left view of the embodiment of the prosthetic heart valve shown in FIG. 78.
FIG. 82 is a right view of the embodiment of the prosthetic heart valve shown in FIG. 78.
FIG. 83 is a top view of the embodiment of the prosthetic heart valve shown in FIG. 78; and,
FIG. 84 is a bottom view of the embodiment of the prosthetic heart valve shown in FIG. 78.
Broken lines are used to illustrate features of the prosthetic heart valve that form no part of the claimed design.
